UNITED STATES PATENT OFFICE.

ALDRED K. WARREN, OF NEW YORK, N. Y.

COLLECTOR FOR THIRD-RAIL SYSTEMS.

SPECIFICATION forming part of Letters Patent No. 761,432, dated May 31, 1904.

Application filed February 25, 1903. Serial No. 144,991. (No model.)

To all whom it may concern:

Be it known that I, ALDRED K. WARREN, a citizen of Great Britain, residing in the city, county, and State of New York, have invented 5 certain new and useful Improvements in Collectors for Third-Rail Systems, of which the following is a specification.

My invention relates to devices for taking current from the main conductor and transferring it to the motor in cars run on what is known as the "third-rail" system.

In the drawings forming part of this specification, Figure 1 is a view illustrating my invention, parts being shown in section. Fig. 15 2 is a front elevation. Fig. 3 is a section taken on the line 3 3 of Fig. 2, parts being broken away. Fig. 3^a is a view showing the invention with a modified form of spring. Fig. 4 is an end view of the pivoted arm and shoe. Fig. 5 is a sectional view thereof. Fig. 20 6 is a plan view showing the guard for the conductor. Fig. 7 is a perspective of the shoe detached.

A represents a bracket which is attached to 25 the car. The form of this bracket is best shown in Fig. 2. It is attached to the car by means of bolts passing through the slots B. The back of the upper end of the bracket is provided with corrugations engaging with those 30 in the piece C attached to the car, thus affording an adjustable connection.

The part lettered A' of Fig. 1 represents the equalizing-bar or portion of the truck-frame, and A^a represents the insulating-piece, usually 35 of wood. The bracket is provided with a lug D, to which is bolted a copper casting E, to which is attached one end of the shunt V, running from the shoe. The bracket, as shown in Fig. 1, is of curved form, though it may be 40 of any form which will adapt it to the particular conditions of the construction of the truck-rail and guard. The bottom of the bracket is provided with lugs F. These lugs are drilled to permit the passage of the pivot- 45 pin G. Freely movable on the pivot-pin G are two arms H H, which are separated by a spacing-piece I. The distance between the two arms H H is less than that between the lugs F for a reason hereinafter stated. The 50 outer ends of these arms H are provided with

lugs J, which are perforated to allow the passage of the pivot-pins K K, on which is placed the contact-shoe L.

M M represent springs the ends of which are coiled around the pivot-pin on either side 55 of the arms H H, the extreme ends being secured in recesses N in the bracket A. The other ends of the wires forming the springs are carried out and turned at substantially right angles to rest on the outer ends of the 60 arms H H. The arms H H, as well as the spacing-piece I, are not only free to move around the pivot-pin G, but are movable lengthwise thereof, being normally kept in the central position by the springs M M. 65

Instead of having the springs M M made as described they may be made of one piece, the ends of which are coiled around the pin, as heretofore stated, the middle portion of the wire being bent in a substantially U shape and 70 bearing on the ends of the arms, as shown in Fig. 3^a. The ends of the arms H H are provided with a plane surface P, eccentrically placed with regard to the pivot. This surface bearing on the bracket prevents the arm from 75 falling down too far.

Instead of making the arms H H separate with a spacing-piece between them I may make said arms and spacing-piece in one, thus forming a single rigid arm, in which case 80 a single pivot-pin only would be used. The advantage of the former construction is that the play of the parts is sufficient to allow a certain tilting of the shoe in the direction of its length, as one of the arms H H would rise 85 sufficiently to allow the shoe to adjust itself to inclines or to pass over a slight obstruction.

I have adopted in my claims the generic term "support" as applied to either or both of the above constructions. 90

The shoe L of the shape best shown in Fig. 7 is provided with lugs Q, drilled to allow the passage of the pivot-pins K. The top of the shoe is grooved, as at R, to allow the easy removal and adjustment of the pivot-pins. The 95 shoe is also provided with a lug S, to which is bolted a copper casting T, which has a socket in which is secured the end of the shunt wire V. The shoe is attached to the arms H H by passing the pivot-pins K K 100

through the lugs at the ends of said arms on the shoe, as clearly indicated in Fig. 3. It will be seen, therefore, that the shoe is free to move in a direction transverse to the length 5 of the conductor W. The ends of the shoe are turned up, as clearly shown in the drawings, as is customary with such devices. From the construction thus far described it will be seen that the shoe is carried on pivot- 10 arms, which arms are kept down by the force of the spring acting directly over the shoe, so that jumping of the shoe from contact with the current-rail is practically prevented, and the shoe being pivoted to move transversely 15 of the rail always rests squarely thereon, notwithstanding the violent swaying of the cars at high speed and irregularity in height of the conducting-rail. Were it not for this pivotal connection, irregularity in height of rails or 20 swaying of the car would often produce very slight or knife-edge contact of the shoe with the rail, leading to sparking and insufficient current to the motors. The arrangement of the spring also serves another purpose— 25 namely, that of a buffer—for the arms H H being free to move lengthwise of their pivot-pin the shock of the shoe against an obstruction or the end of a contact-rail will be taken up by the operation of that part of the spring 30 coiled around the pivot-pin G.

In Figs. 1 and 6 I have illustrated a form of guard for the contact-rail, though I do not in this application lay claim thereto. This guard *a* consists of a curved piece of metal of any 35 suitable material placed directly over the rail and at a suitable distance therefrom. The guard is made in comparatively short sections, separated from each other as indicated in Fig. 6, so that the accidental contact of the shoe 40 with the guard will charge but a small section of the guard. The guard is supported by brackets *b*, which are in turn secured to the rail-ties or any suitable part of the structure. This avoids any necessity for insulation 45 of the guard.

Serious difficulty has been met in third-rail systems due to the breaking of the shunt-wire running from the shoe to the motor. This is usually run direct, and the constant swaying 50 and motion of the cars causes constant bending of the wires at a certain point or points, which in a comparatively short time causes

the same to break. I overcome this difficulty by means illustrated in Fig. 5. Instead of leading the shunt-wire V direct to the socket 55 E, I coil such wire around the spacing-piece I, the coil being loose, as clearly shown in the drawings. By this arrangement it will be seen that the motion of the pivoted arm will simply cause the coil to loosen or tighten, the 60 strain on the wire being practically in a straight line.

I claim—

1. In a collector for electric railways, the combination of a support pivoted to the car, a 65 shoe attached to the end of said support adapted to bear on the conducting-rail, and a spring bearing on said support to prevent breaking the contact between the shoe and the rail, one end of said spring being disposed 70 to form a buffer for said support, substantially as described.

2. In a collector for electric railways, the combination of a bracket attached to the car, said bracket having lugs thereon, a support 75 pivoted between said lugs, a shoe attached to the end of said support and bearing on the contact-rail, a spring bearing on the end of said support, the ends of said spring being coiled around the pivot-pin of the support between 80 said support and lugs, substantially as described.

3. In a collector for electric railways, the combination of a support pivoted to the car, a shoe at the end bearing upon the contact- 85 rail, a shunt-wire running from said shoe to the motor connection on the car, said wire being disposed in a coil around the pivotal part of said support, substantially as described.

4. In a collector for electric railways, the 90 combination of separate arms pivoted to the car and movable independently of each other, a shoe pivotally secured to the ends of said arms and adapted to bear on the contact-rail, and a spring-pressure device normally tending 95 to keep the shoe in contact with the rail, substantially as described.

In testimony whereof I have hereunto set my hand, in the city, county, and State of New York, this 16th day of February, 1903.

ALDRED K. WARREN.

In presence of—

E. M. HARMON,
H. J. LILLIE.
